UNITED STATES PATENT OFFICE.

ELBERT HAMILTON SEARLE, OF PHILADELPHIA, PENNSYLVANIA, ASSIGNOR OF THREE-FOURTHS TO WILLIAM D. CONDIT, OF DES MOINES, IOWA.

GUN.

936,369.

Specification of Letters Patent. Patented Oct. 12, 1909.

Application filed April 25, 1907. Serial No. 370,338.

To all whom it may concern:

Be it known that I, ELBERT HAMILTON SEARLE, a citizen of the United States, residing at Philadelphia, in the county of Philadelphia, in the State of Pennsylvania, have invented certain new and useful Improvements in Guns, of which the following is a specification.

This invention relates to semi-automatic, recoil actuated, magazine guns.

One object of my invention is to provide an automatic firearm which will be relatively inexpensive to manufacture, simple in operation, and durable and reliable in use.

Other objects are to provide an improved means for connecting the barrel and the breech bolt to the frame; means for automatically interlocking the barrel and breech bolt at time of firing; an improved grip; an improved means for securing the firing pin in the breech bolt; an improved means for securing the safety lock; an improved firing mechanism; an improved follower-operated lock; an improved magazine; and an improved manner of mounting.

Other and further objects will appear in the following description and will be more particularly pointed out in the appended claims.

While I have shown and described my invention as applied to a firearm, in which several of the functions are performed automatically as a result of firing, it is to be understood that with slight changes, some of the parts may be adapted for use in any type of gun, automatic or non-automatic.

In the drawings, Figure 1 is a side elevation of a gun. Fig. 2 is an opposite side view, one wall of the pistol being broken away to show inner parts in elevation, the breech bolt being closed and the firing pin being released. Fig. 3 is a vertical longitudinal section, the breech being locked open by the follower-operated lock and parts being broken away to show the follower-operated lock. Figs. 4 and 5 are respectively a bottom view and a longitudinal vertical section of the breech bolt and extension. Figs. 6 and 7 are transverse vertical sections respectively on the lines 6-6 and 7-7; Fig. 4. Fig. 8 is a plan view of the frame with all other parts removed. Figs. 9 and 10 are plan views of the breech bolt plug and firing pin respectively. Figs. 11 and 12 are respectively a top view and a rear end eleva-

tion of the firing spring abutment. Figs. 13 and 14 are respectively a side elevation and a top view of the sear. Fig. 15 is a detail of the cocking lever and parts coöperating therewith. Figs. 16 and 17 are respectively a side view and a rear view of the ejector. Fig. 18 is a detail view of the safety lock. Figs. 19 and 20 are respectively a side view and a top view of the trigger. Fig. 21 is a top view of the trigger and sear connector. Figs. 22 and 23 are respectively a side view and a top view of the follower-operated breech bolt lock. Fig. 24 is a section on line 24-24, Fig. 1. Figs. 25 and 26 are detail views of the magazine box. Fig. 27 is a side view of the firing mechanism removed. Fig. 28 is a plan view of the firing mechanism removed. Fig. 29 is a perspective view of the ejector and the safety lock. Fig. 30 is a detail view of the follower-operated breech bolt block. Fig. 31 is a detail view of another form of lost motion connection between the exposed portion of the cocking lever and the firing pin.

General construction. Referring more particularly to the drawings, A indicates a frame provided with a grip 1 having a magazine chamber 2 to receive magazine box B to be hereinafter more particularly described. In front of the grip the frame is provided with a trigger guard 3. The upper part of the frame is provided with longitudinally inwardly turned overhanging tracks or guides 4 upon which travel the breech bolt C and its extension D, these parts being provided with outwardly turned tracks or guides 5 which fit between and under the overhanging tracks 4.

The gun is assembled by first inserting the lug 6, on the under side of the barrel E, between two shoulders 7 and 8 integral with the frame A, the shoulders permitting the barrel to rotate but holding it against movement in the direction of its bore. The breech bolt C having an extension D, of tubular formation at its front end 9, is then fitted over the front end of the barrel, a helical spring 10 having been first introduced within the tubular portion 9 and abutting against an inwardly turned flange 11 at the front end of said portion. The rear end of spring 10 enters into engagement with an annular shoulder 12 on the barrel shortly after the breech bolt extension is fitted about the barrel and a continued move-

ment of the breech bolt to the rear, places the spring under compression. When the breech bolt has reached its extreme limit of rearward movement, the breech bolt plug *c* is introduced in the breech bolt in rear of the barrel, and interlocked therewith, so as to provide the breech closure and limit the forward movement of the breech bolt under the influence of spring 10.

10 *Connection between breech bolt and its plug.*—For the purpose of interlocking the breech bolt plug *c* with the bolt *C*, I provide the following means. The bolt is provided on opposite inner side walls with enlargements or projections 13 while the plug is provided with two pairs of enlargements 14 and 15 respectively, the members of each pair being on opposite sides of the plug and the pairs forming between them depressions 16 on each side of the plug. All the mechanisms carried by the plug lie entirely within the lines of the plug and it is thus possible to introduce the plug while it is turned 90° from its normal position, so that the front pair of enlargements on the plug will pass between the enlargements 13 on the breech-bolt. After the enlargements 13 have been passed, and the shoulder 18 on the plug engages the rear end of the extension, the plug 25 is turned to cause the said enlargements 13 to enter the depressions between enlargements 14 and 15 on the plug, which is now held against axial displacement relatively to the breech-bolt.

30 *Lock for breech closure.*—I utilize in this invention, as in my previous patent No. 804,985, dated November 21, 1905, the tendency of a rifled barrel to rotate when a projectile passes therethrough, as a means for locking the breech-bolt against opening movement, until the projectile has passed from the barrel. In the present instance, the barrel is provided on the upper side, at the rear, with a lug 16, beveled at 16°, (see 35 dotted lines Fig. 4) which lies against a beveled shoulder 17 on the inner top wall of the breech-bolt when the breech is closed. When the gun is fired, the inertia of the projectile overcome by the rifling of the barrel in inducing rotation, causes the lug to be held firmly against shoulder 17 and to positively lock the breech bolt against rearward movement under pressure of the powder gases, until the projectile leaves the 40 barrel, when the barrel will be free to turn, and the breech-bolt may move rearwardly under the force of recoil, the projection 16 being displaced by the beveled faces 16°—17, and longitudinal groove 18° in the top of the 45 breech bolt extension, permitting the latter to travel over projection 16. The breech bolt and its extension are returned to close the barrel breech by means of the spring 10.

50 As the breech-bolt moves rearwardly, an ex- 55 tractor 19 mounted therein through the

medium of plug *c* engages the rim of the spent cartridge and draws said cartridge from the barrel. As the breech bolt nears the end of its rearward movement, an ejector 20, projecting from the frame, kicks the cartridge through the opening 21 in the breech bolt extension *D*.

55 *Ejector and safety lock.*—The ejector 20 (see Figs. 16, 17 and 29) is mounted upon the frame *A* below the plug *c* of the breech-bolt *C* on the side opposite that on which the extractor and the opening 21 are located, and for this purpose, the frame *A* is provided with a vertical recess 22 in which fits a stud 23 on the ejector. The ejector projects upwardly from the frame and works in a groove, 20° (see dotted lines, Fig. 2) in the lower portion of the breech-bolt plug *c*, and thus presents itself in proper relation to the cartridge shell, and at the same time 85 serves to prevent the plug rotating to release position. The ejector also serves to secure the safety lock 24.

90 The safety lock (see Figs. 18 and 29) is adapted for locking the breech bolt in open and in closed position. It is further adapted for locking the firing mechanism against action as will hereinafter more fully appear. Said safety lock comprises a rotary spindle 24 provided with a diametric slit 25 which 95 permits its slight compression in entering its seat and thereby causes it to be held with friction against the walls of said seat, provided by a circular opening 26 in the frame *A* adjacent one of the tracks or guides 4. 100 The lock is further provided with a notch 26° which permits the free movement of the breech-bolt on the tracks 4 but when the spindle 24 is turned by means of handle 27 and either notch 28 or notch 29 is located 105 above the spindle, the curved portion of the spindle will enter said notch 28 or 29 and lock the breech-bolt and its extension against movement. If the notch 29 is disposed over the lock, the breech bolt will be locked closed, 110 and if the notch 28 is disposed over the lock the breech-bolt will be locked open (see Fig. 3). The end of the safety lock is provided with a diametric groove 30, the purpose of which will hereinafter appear. The safety 115 lock is held in the frame by a portion 20° on the ejector 20, extending into a circumferential groove 24° in the spindle 24.

120 *Firing mechanism.*—The breech-bolt plug *c*, (see Figs. 2, 3, 9, 10 and 31) is provided with an inclined bore in which works a firing pin or striker 31 having a reduced rear portion 32 and two laterally extending lugs or projections 33. A helical spring 34 surrounds the reduced portion 32 and abuts at 125 its front end, the shoulder 35 formed by the reduced portion. The rear end of the spring abuts the removable abutment 36. The removable abutment is of cylindrical formation except its rear outer face 37 which is 130

flattened and provided with a vertical slot 36* through which the firing pin 31 works. The plug *c* is provided with a transverse circular bore 38 in which fits the removable 5 abutment 36. It is apparent that when the breech-bolt plug *c* is introduced into the breech bolt *C* the abutment will be held against displacement.

Cocking mechanism.—The means for cocking 10 the firing pin comprises a lever 39 pivoted at 40 intermediate of its ends to the breech-bolt plug and having its front face grooved or bifurcated at 41. The walls of 15 the groove or bifurcation 41 are provided with openings 42 to receive the lugs 33 on the firing pin, the upper portion 41^a of the groove 41 being as wide as the distance between the extreme ends of the lugs 33 so that this end of the firing pin may be inserted therethrough and dropped into the 20 openings 42. The openings 42 have greater diameter than the lugs to provide a lost motion connection between exposed portion of the cocking lever and the firing pin, whereby 25 the exposed portion of the cocking lever may engage the end of the breech-bolt, and any shock imposed upon the cocking lever is not transmitted to the firing pin, thus preventing accidental detonation. On its exposed 30 upper end the cocking lever is knurled or roughened as at 43, whereby the gun may be cocked by hand. To automatically cock the lever, its lower end is provided with a roller 44 which travels on the rear inner wall 35 45 of the frame *A* on the rearward movement of the breech-bolt and causes the upper end of the lever to withdraw the firing pin.

Locking the firing pin in cocked position.—The cocking lever is provided with a 40 lateral lug 54 which, when the breech-bolt closes the barrel and the firing pin is in retracted position, lies directly over the safety lock spindle 24. Should the groove 30 in the end of the lock lie substantially vertical as 45 shown in dotted lines, Figs. 2 and 3, then, when the firing pin is released, the lug 54 will pass through the groove. But should the safety lock be turned, as in Fig. 15, so that the lock lies in the path of the lug 54, 50 it would be impossible to release the firing pin.

Sear.—As the firing pin 31 is drawn back by the cocking lever 39, a sear (see Figs. 2, 3, 13 and 14) drops in front of a shoulder 46 on the firing pin. This sear has an off-set arm 47 which lies within a slot 48 in the bolt plug *c*, and engages at one end with the shoulder 46, and at its other end is provided with a rounded bearing 49 seating in a 55 concave bearing 50, at the front end of the slot 48. Another arm 51 extends downwardly on one side of the breech-bolt plug from arm 47. Arm 51 has a face 52 which is engaged by a spiral spring 53 located within a recess

in the breech-bolt plug. The sear is held to 65 its seat by the breech-bolt proper, which encloses the top of the breech-bolt plug.

Sear connector and trigger.—The trigger 55 is mounted within the trigger guard 3 and extends at its upper end to a seat 56 below the barrel. The trigger is adapted for 70 sliding movement on the seat 56 and has pivoted to its front end at 57 a trigger-and-sear connector which has a portion 58 working in a slot 59 to one side of shoulders 7 75 and 8 on the frame, so that if the trigger is pulled or slid to the rear, and the breech-bolt is in firing position, the connector will engage the lower end of arm 51 of the sear and release the firing pin. 80

Locking sear connector until trigger is released.—As the breech-bolt moves rearward after firing, a cam face 60 on its extension engages a cam face 61 on the connector and moves or depresses the said connector so that it will not be in a position to engage the sear upon the return of the latter to firing position. To hold or lock the connector in this position, until the trigger is released and thereby prevent double 90 firing, I provide the following means: The connector 58 has a housing extension 62 which overhangs the forward part of trigger 55, the trigger being cut or recessed at 63 to receive the housing 62 and to permit the connector to be depressed entirely within the 95 plane of the trigger. When the trigger 55 is drawn back to actuate the sear, a latch or plunger 64 has its beveled end 65 brought up against a vertical wall or face 66 on the frame *A* and as the plunger is being depressed a spring 67, which at one end abuts against the plunger or latch 64, is compressed. As the connector reaches the end 100 of its movement, the plunger moves rearward under the action of its spring 67 and enters a recess 68 in said wall, thus locking the connector in its depressed position. The connector stays in this position until the trigger is released, and as it is impossible 105 for one to release the trigger before the breech-bolt has returned to its original or firing position, owing to the great rapidity at which the automatic opening and closing of the breech takes place, it follows that 110

double firing cannot occur. Upon the release of the trigger, the coil spring 69 causes the trigger 55 to slide or move forward on its seat 56. As the trigger moves forward, the plunger 64 is withdrawn from the recess 115 68 and the spring 67 which also acts upon a hollow plunger 70 also carried by housing 62, is permitted to expand and force the hollow plunger 70 to ride upwardly on the inclined wall 71 of the recess 63, thus elevating the rear end of the connector into a 120 position that it can engage the sear when the trigger is again pulled. Of course, on 125

the downward movement of the connector the plunger 70 also moves to compress spring 67. To limit the outward movement of the plunger or latch 64, said latch carries a projection 72 which engages a lug 72^a on one side of the connector portion 58.

Grip.—The grip 1, before mentioned, as stated, has a magazine chamber 2, the side walls of which are partially formed of plates 10 73 which may be of hard rubber, stamped metal or any other suitable elastic material. These plates are slid onto the grip and are held by means of overhanging tracks or guides 74 which lead from the rear of the 15 grip. When the plates are in proper positions on the grip, lugs 75 thereon snap into recesses 76 on the grip and hold the plates in position. To remove the plates, one's fingers are introduced into the magazine 20 opening through the bottom of the grip, and pressure is applied to the plates at those portions adjacent the lugs 75. The plates are then slid to the rear. At the front edges of the plates, the grip is provided with vertical 25 grooves 77 into which project fins 78 on the plates, the interlock between the parts preventing the plates working or having play on the grip.

Magazine box.—The magazine box is 30 formed from a strip of metal into a body 79 of rectangular cross section, the lower end of the body being closed by a plate 80. The plate has its ends provided with inwardly turned portions or flanges 81 which are 35 adapted to receive the pair of outwardly turned flanges 82 on the end of the magazine body, the plate being connected to the body by a sliding movement. To prevent the plate sliding off the body, two bosses 83 40 are struck or pressed up from the plate to engage the inner side walls of the body.

The magazine box contains a follower 84 pressed upwardly by a spiral spring 85; to hold the box within the magazine chamber 45 2, there is provided a lever or latch 93 pivoted intermediate of its ends at 93^a in a vertical slot 94 in the lower front portion of the grip, the lower end of the lever being provided with a nose 93^b adapted to enter 50 an opening 2^a in the lower end of the magazine and the upper end of the lever lying within a notch 94^a in the grip. The latch is normally held in locking position by a coil spring 95 which lies within an opening 95^a in the lever and projects from opposite sides of the latter. The projecting portions of the spring fit within two grooves 94^b in opposite walls of the slot 94, the outer end of the spring seating against the end walls of 55 the grooves. By positioning the latch at the lower end of the grip two results are obtained; first, the latch is covered by the hand in firing, and thus accidental operation of the latch is prevented, and secondly, it is 60 thus as near as possible to the center of os-

cillation, so that the shocks induced by recoil will not operate the latch.

Follower operated lock.—When the magazine is filled, the follower is of course near the bottom of the box. As the cartridges are fed, one by one from the box, the follower rises and after the last cartridge is fed to the barrel and the breech-bolt moves rearwardly under the action of the firing, the follower engages a shoulder 86^a on a bolt lock 86. This bolt lock 86 is fulcrumed in the side wall of the grip by means of a rounded offset 87 integral with the lock, bored to provide a thin rear wall, having said wall divided to render it yielding, and projecting into a recess 88 in the wall of the grip, where it is held by the overlapping plate 73. As the bolt lock is swung on its pivot, a projection 89 on the bolt lock is swung upwardly and when it reaches its upper position, the projection 89 enters a notch 90 in the breech-bolt extension and holds the breech-bolt open until the said breech bolt is released. To release the breech-bolt, an extension 91 on the bolt lock 90 is depressed. This extension or finger piece extends from the lock through an opening 92 in the frame to a point to one side of the trigger 53.

Strap swivel.—Strap swivels heretofore employed have been so mounted as to be in the way when the pistol is used. To obviate this disadvantage the rear lower portion of the grip is bifurcated and the arm 97 of the swivel is fitted in the bifurcation. The bifurcation extends entirely through the rear wall of magazine opening 2 so that the swivel may be swung into the magazine opening, the rear wall of the opening being spaced from the box wall so that there is formed a pocket in which the swivel may lie when the box is fitted in place as shown in Fig. 3.

Embodiment shown in Fig. 31.—Another embodiment of the lost motion connection between the striker or firing pin and the exposed rear of the cocking lever is shown in Fig. 31. In this embodiment the cocking lever is formed of two parts, one portion 39 being pivoted intermediate its ends at 40, rolling on the inclined surface 45 at its lower end and pivotally connected at its upper end at 35^a with the rear end of the firing pin 31^a, and the other or exposed rear portion being in the form of a hood 39^b pivoted at 40, and having its upper front edge adapted to engage the breech-bolt plug *c*. It will be noted that any blows on the rear exposed portion will be transmitted to the plug, and not to the firing pin and that therefore the firing pin may lie against a cartridge in the barrel without danger.

Having thus described my invention what I claim is:

1. The combination with the frame, of the

barrel rotatably mounted and having a lug, a breech bolt having a breech-closing portion movable to and from the barrel, and a slotted breech-bolt extension slidably mounted upon the frame, surrounding the barrel, and having its inner top wall provided with a shoulder to be engaged by the barrel lug, and with a longitudinal groove leading from said shoulder, said lug, shoulder and groove being circumferentially removed from the slot in the breech-bolt extension.

2. In a recoil actuated gun the combination of the frame, the barrel having a lug engaging the frame and fixing the barrel against longitudinal movement, but permitting it to rotate thereon, the reciprocating breech-bolt having an extension which surrounds the barrel, slotted to provide a bearing on the frame on the side opposite the lug which fixes the barrel on the frame, and having an interlock with the barrel, and adapted to hold the breech bolt against recoil until the projectile has left the barrel.

3. The combination of the frame, the barrel, the breech-bolt surrounding the barrel and slidably mounted on the frame, and the breech-bolt plug inserted within and carried by the breech bolt; said breech bolt having its bearings upon the frame extending below the breech-bolt plug, and having a rearward opening through which the breech-bolt plug may be inserted and withdrawn.

4. The combination of the frame, the barrel, the breech bolt slidably mounted on the frame, and the breech bolt plug inserted within and carried by the breech bolt; said breech bolt having a rearward opening through which the breech bolt plug may be inserted and withdrawn, and said breech bolt plug and breech bolt having means through which they interlock by relative rotation; the parts of the plug being limited in dimensions to the internal diameter of the breech bolt to permit such rotation.

5. The combination of the frame, the barrel, the breech bolt slidably mounted on the frame, and the breech bolt plug inserted within and carried by the breech bolt; said breech bolt having a rearward opening through which the breech bolt plug may be inserted and withdrawn, and said breech bolt plug and breech bolt having means through which they interlock by relative rotation; the parts of the plug being limited in dimensions to the internal diameter of the breech bolt to permit such rotation, and means engaging said plug to prevent such rotation when the breech bolt is forward of its retracted position.

6. The combination of the frame, the barrel, the breech bolt slidably mounted on the frame, and the breech bolt plug inserted within and carried by the breech bolt; said breech bolt having a rearward opening

through which the breech bolt plug may be inserted and withdrawn, and said breech bolt plug and breech bolt having means through which they interlock by relative rotation; the parts of the plug being limited in dimensions to the internal diameter of the breech bolt to permit such rotation, and means engaging said plug to prevent such rotation when the breech bolt is forward of its retracted position, consisting of the ejector carried by the frame, and entering a groove in a recoiling part.

7. The combination with the frame, of the barrel, the breech bolt having sliding bearings on the frame in rear of the barrel and having an extended portion surrounding the barrel and the breech-bolt plug having a rotary interlocking connection with the breech bolt.

8. In a recoil operated fire arm the combination of a tubular breech bolt having projections on opposite inner walls, and a breech bolt plug movable longitudinally into the breech-bolt and having two shoulders constructed to pass between the projections on the breech bolt and to interlock with said projections when the breech bolt is rotated.

9. The combination with a frame, of a safety lock, and an ejector having a portion holding said lock to the frame.

10. The combination with a frame, of an ejector and a safety lock, one of said parts holding the other to the frame.

11. The combination with a frame, of a safety lock rotatable in the frame, and provided with an annular groove, and an ejector fitted in the frame and provided with a portion extending into the groove to hold the safety lock against axial displacement.

12. The combination with a reciprocating breech bolt, and a firing pin carried thereby, of a cocking lever pivoted to the breech bolt and having lost motion connection with the firing pin.

13. The combination with a fire arm having a percussive firing device; a reciprocating breech bolt having a cocking member pivotally mounted thereon, said member having lost motion connection with the firing device and an abutment against which the cocking member rests when the firing device is in projected position, and by which the cocking member is sustained against external percussion and prevented from transmitting the same to the firing pin.

14. The combination with a reciprocating breech bolt of a firing pin carried thereby and provided with lugs upon opposite sides, a cocking lever pivoted to the breech bolt provided with a bifurcated front face and with two openings in the arms of the bifurcation into which the lugs on the firing pin project.

15. The combination with a rearwardly sliding breech bolt, and a firing pin carried

- thereby, of a cocking lever pivoted intermediate of its ends to the breech bolt, connected at its upper end to the firing pin and at its lower end engaging the frame, a lug on one side of the cocking lever, and a safety lock having its end provided with a diametric groove which in one position permits the passage of the lug therethrough and in another position prevents said passage.
16. The combination of a breech bolt plug having a transverse bore, a firing pin carried by the plug, a spring for the firing pin, and an abutment for the spring fitting in the transverse bore.
17. The combination with a breech bolt, of a breech bolt plug having an interlocking connection with the breech bolt, a firing pin carried by the breech bolt plug, a spring for the firing pin, and a removable abutment for the spring held in the breech bolt plug by the inner wall of the breech bolt.
18. The combination with a breech bolt, of a breech bolt plug having a rotary interlocking connection with the breech bolt, a firing pin carried by the breech bolt plug, a spring for the firing pin, and an abutment removable transversely of the breech bolt plug and held in place by the wall of the breech bolt.
19. The combination with a breech bolt, of a breech bolt plug having a rotary interlocking connection with the breech bolt, a firing pin carried by the breech bolt plug, a spring for the firing pin, and an abutment removable transversely of the breech bolt plug, held in place by the breech bolt, and provided at its rear with a vertical slot through which projects one end of the firing pin.
20. The combination with a breech bolt, of a breech bolt plug having an interlocking connection with the breech bolt, and provided with a slot in its top, a firing pin carried by the breech bolt plug, a sear having an arm working in the slot to engage the firing pin and seated in the breech-bolt-plug at the front end of the slot, said sear also having an arm depending on one side of the breech-bolt-plug, said sear being held to its seat by the inner wall of the breech bolt, and means for operating the sear.
21. The combination with a breech bolt, of a breech bolt plug having an interlocking connection with the breech bolt, and provided with a slot in its top, a firing pin carried by the breech bolt plug, a sear having an arm working in the slot to engage the firing pin and seated in the plug at the front end of the slot, said sear also having an arm depending on one side of the plug, said sear being held to its seat by the inner wall of the breech bolt, a spring acting on the depending arm of the sear, and means for operating the sear.
22. The combination with a sear, of a sliding trigger, and a sear and trigger connector pivotally supported by the trigger.
23. The combination with a part movable automatically upon firing, of a sear, a sliding trigger, and a sear and trigger connector pivotally supported by the trigger and moved by the automatically moving part to prevent the sear being engaged by the connector.
24. The combination with a sear, and a trigger, of a connector between the sear and the trigger, means operated by the recoil of the gun to displace the connector from the sear, and means independent of said displacing means, holding the connector to prevent it returning to operate the sear; said holding means being released by the forward movement of the trigger.
25. The combination with a part moving automatically upon firing, of a sear carried by said part, a trigger, a connector between the sear and the trigger, and means moved by the automatically moving part to hold the connector and prevent said connector operating the sear until the trigger is released.
26. The combination with a sear, and a trigger, of a connector between the sear and the trigger, and a latch carried by the connector and holding the same to prevent it operating the sear until the trigger is released.
27. The combination with a part moving automatically upon firing, of a sear secured to said moving part, a trigger, a connector between the sear and the trigger, a latch carried by the connector for holding the same to prevent it operating the sear until the trigger is released, said latch being controlled by the automatically moving part.
28. The combination with a trigger, and a sear, of a connector pivotally supported by the trigger, and a latch carried by the connector and holding the same to prevent it operating the sear until the trigger is released.
29. The combination with a sear, and a trigger, of a longitudinally movable trigger and sear connector, and a latch for the connector inoperative when the trigger is released.
30. The combination with a frame, an automatically moving breech bolt having an extension and a breech bolt plug, of a sear carried by the breech bolt plug, a trigger carried by the frame, and slidably thereon, a trigger and sear connector pivoted to the trigger, and depressed by the breech bolt extension, and means for locking the connector depressed until the trigger is released.
31. The combination with a frame, an automatically moving breech bolt having an extension and a breech bolt plug, of a sear carried by the breech bolt plug, a trigger car-

ried by the frame, and slideable thereon, a trigger and sear connector pivoted to the trigger, and depressed by the breech bolt extension, and a latch carried by the connector 5 and engaging the frame.

32. The combination with a frame, a sear, and a trigger, of a depressible connector between the sear and the trigger, a latch carried by the connector engaging the frame 10 when the connector is depressed, and means automatically depressing the connector upon the firing of the gun.

33. The combination with a frame, an automatically moving breech bolt having an 15 extension and a breech bolt plug, of a sear carried by the breech bolt plug, a trigger carried by the frame, and slideable thereon, a trigger and sear connector pivoted to the trigger, and depressed by the breech bolt extension, a latch carried by the connector and engaging the frame, and means raising the connector when the trigger is released.

34. The combination with a sear, of a sliding trigger, a depressible connector between 25 the sear and the trigger, pivoted to the trigger, means automatically depressing the connector when the gun is fired, a latch carried by the connector and engaging the frame when the connector is depressed and the trigger is pulled, a plunger carried by the connector and acting on the trigger to elevate the connector and a single spring acting on the latch and the plunger.

35. In a fire arm, having a reciprocating 30 breech bolt and a magazine follower, a breech bolt stop pivoted in the side wall of the grip, extending across one face of the magazine, having an arcuate bearing at its opposite end and constructed to overlap the follower and intersect the path of the bolt.

36. In a fire arm having a reciprocating breech bolt, and a magazine follower, a bolt stop comprising a segmental member provided with pivotal and arcuate end-thrust 45 bearings at its respective ends, constructed to intersect the path of the follower and adapted to travel into the path of the breech bolt.

37. In a fire arm having a reciprocating

breech bolt, and a magazine follower, a bolt stop comprising a segmental member provided with pivotal and arcuate end-thrust bearings at its respective ends, constructed to intersect the path of the follower and adapted to travel into the path of the breech bolt; 55 one of the bearing ends being resilient to maintain friction between the stop and its bearings.

38. In a fire arm having a suitable frame, grip, magazine located in the grip, a removable plate on the side of the grip, and a reciprocating breech bolt; a breech bolt lock having a bearing in the side wall of the grip into which the lock is introduced laterally; 60 said lock lying immediately beneath the side 65 plates of the grip and confined in its bearing by said side plate.

39. In a fire arm having a frame, a grip, a magazine located in the grip, a reciprocating breech bolt, and a trigger; a breech bolt lock 70 moved vertically by a part moving with the cartridge feed into engagement with the breech bolt, and having a projection through which it is released, extending through the grip into position to receive the end of the 75 trigger finger.

40. A pistol grip comprising a frame and a side plate engaged on two edges by the frame to confine the plate in one direction, and engaging said frame at a third edge to 80 confine it in a second direction, said plate having inherent resiliency which permits it to be sprung out of the said engagement in said direction, to release the plate.

41. The combination with a rearwardly 85 sliding breech bolt, of a striker carried thereby, a cocking lever for the striker provided with a lug on one side thereof, and a rotary safety lock having its end provided with a diametric groove which in one position permits the passage of the lug and in another position prevents said passage.

The foregoing specification signed at Utica, N. Y., this 7 day of January, 1907.

ELBERT HAMILTON SEARLE.

In presence of two witnesses—

J. SCHLICKER,

E. A. LOOMIS.
